UNITED STATES PATENT OFFICE.

LOUIS FORT, OF JERSEY CITY, NEW JERSEY.

LINE-WIRE INSULATOR.

1,292,451.

Specification of Letters Patent. Patented Jan. 28, 1919.

Application filed April 13, 1915. Serial No. 20,999.

To all whom it may concern:

Be it known that I, LOUIS FORT, a citizen of the United States, and a resident of Jersey City, in the county of Hudson and State 5 of New Jersey, have invented certain new and useful Improvements in Line-Wire Insulators, of which the following is a full, clear, and exact description, whereby any one skilled in the art may make and use the 10 same.

The invention relates to insulators and more particularly to line wire insulators of the so-called "petticoat" type.

Petticoat insulators are acknowledged to 15 be one of the best types or forms of insulator for securing the highest degree of insulation between a live wire and the ground but in the use of an ordinary petticoat type of insulator which is most efficient, there is 20 a disadvantage in that the line wire must be secured to the insulating body-part by a tie-wire or marlin or other material which passes about the insulator and is wrapped about the wire. It is the principal object 25 of the present invention to maintain the high efficiency of the petticoat type of insulator and provide in conjunction therewith, a clamping means for securing the wire.

It is also an object of the invention to 30 provide a clamping device of universal form, that is, one which will carry horizontally disposed wires or vertically disposed wires.

A still further object is to provide a form 35 of device which may be made applicable to any well-known petticoat type of insulator, insuring perfect clamping of the wire with all the advantages of high insulation to ground. An important object of the invention 40 is to provide a securing device in conjunction with a petticoat type of insulator which will avoid establishing a complete metallic circuit which would ordinarily form a secondary inductive circuit where the 45 devices are used on high tension circuits.

Referring to the drawings:

Figure 1 is a sectional view through a petticoat insulator.

Fig. 2 is a view in side elevation of the 50 insulating members of a clamp.

Fig. 3 is a view in elevation of the device of Fig. 1, looking from the left of said figure.

Fig. 4 illustrates the clamping members in 55 position to retain a horizontally disposed wire.

Fig. 5 illustrates the device when used with vertically disposed wires.

Fig. 6 illustrates a clamping hook used in conjunction with the parts as arranged in 60 Fig. 4.

Fig. 7 is the clamping yoke used with the parts disposed as in Fig. 5.

Fig. 8 is a view similar to Fig. 4, illustrating all the clamping members formed 65 separately and conforming to and fitting a petticoat insulator.

Fig. 9 is similar to Fig. 5, illustrating all the clamping parts formed separately and conforming to and fitting a petticoat insu- 70 lator.

Fig. 10 is a modified form of insulator embodying the invention.

Fig. 11 is a bottom plan view of the de- 75 vice of Fig. 10.

Fig. 12 is a rear face view of the petti- coat clamp member.

Fig. 13 is a face view of the co-operating clamp member.

Fig. 14 is a view illustrating the clamping 80 part of the insulator conforming to the petticoat insulator and of the type illustrated in Fig. 10 arranged for a vertically disposed wire.

Fig. 15 is a view similar to Fig. 14, show- 85 ing the arrangement of parts for horizontally disposed wires.

Fig. 16 is a detail view of a washer plate.

While the petticoat type of insulator is 90 well recognized as most efficient, it has cer- tain faults and inconveniences in use which are almost inherent characteristics.

Such devices are ordinarily placed upon the pins of a cross-arm or bracket and the line wire is secured thereto by passing a 95 wire about the insulator and winding it over the wire, thus forming a "tie-in." It has also been a common practice to use marlin or soft materials so that there would be less of an abrading effect upon the wire but in 100 any case, the wires are abraded and insulation is decreased and there is thus a less perfect insulation between the conductor and "ground."

Furthermore, where metallic material is 105 used for tying in or metallic clamps are employed, a secondary circuit is established which is most undesirable. The present invention overcomes these various objections and incidentally provides a device 110 of universal application wherein vertically disposed or horizontally disposed line wires

may be securely clamped with a maximum of insulation between the conductor and "ground." Furthermore, the device is so arranged that in the event of the insulator being fractured, the wire will not drop from the pin but will be held by certain of the clamping members against dislodgment. With the ordinary petticoat insulator, it is a usual occurrence when the insulator is broken for the wire to drop down.

Referring to the drawings, there is an insulator of petticoat type having a body-part 1 provided with the usual irregular grooved surface and having extending from one side (as illustrated in Figs. 1 to 5) or arranged to be clamped on one side (as illustrated in Figs. 8 and 9), a boss 2. There is, of course, a central opening for the pin as at 3 and the petticoat formation 4 at the bottom of the insulator. The boss 2, as illustrated in Fig. 1, has an angularly formed opening 5 which as shown, is of square cross-section and tapered. Fitting this opening is a similarly formed lug 6 extending from the rear face of a clamping member 7. This clamping member 7 and its coöperating member 8 are formed of insulating material and each is provided with gripping recesses 9, 10 of a proper form to engage a wire. The form illustrated is particularly adaptable for the twin-wire type of conductor, and may of course be serrated.

The clamp member 7 has extending from it an angularly formed rib 11 and a similarly formed recess 12. The latter registers with a boss 13 and the former with a groove 14 formed in the insulating member 8.

When the clamping parts are arranged to hold horizontally disposed wires, a pair of clamping hooks 15 having loops 16 and extended ends 17 are passed about the grooves 18, 19 at the upper and lower portions of the insulator and are then passed through perforations 20, 21 in the respective clamp members 7 and 8. On the rear face of the clamp member 8 are arranged washers or plates 22 which preferably have angularly formed openings 22^a to prevent their turning on the shanks 17 of the hooks. Nuts or other suitable clamping devices 23 bind the parts together. The purpose of using extended plates 22 which, it will be observed, do not come in contact with each other, but are separated by an insulating boss 24, is to prevent a continuous metallic circuit about the conducting wire and the insulator. This breaks what otherwise will be a secondary circuit. The plates also have a further function in that they, with the hooks 15 serve as a retainer for holding the conductor to the pin in the event of the parts of the insulator or clamp becoming broken.

When the clamp is used for supporting a vertical wire, the clamp parts 7, 8 are transposed relatively to the petticoat body-part 1 as illustrated in Fig. 5. In this case, a U-shaped clamping rod 25 is employed and this is passed about the central groove 26 of the petticoat insulator.

In lieu of forming the boss 2 directly upon the petticoat insulator, the device may be formed as illustrated in Figs. 8 and 9, 75 where the same forms of clamping hooks or U-shaped clamping members are employed but where the petticoat insulator 26^a is of the ordinary well known type without a boss formed on one side and integral therewith. In this case, the clamping member 27 has an extended seat portion 28 which conforms to the surface of the insulator and may be firmly seated there-against when its coöperating clamp member 29 is 85 drawn into position by the clamping hooks.

In Fig. 9, the same arrangement is illustrated with the base-part 28 of the clamping member 27 conforming to the surface of the petticoat insulator 26^a and with the 90 clamping parts disposed for receiving a conductor extending vertically.

In Figs. 10 to 13, there is shown a slightly modified type of petticoat insulator which lacks the upper and lower grooves of Fig. 95 1. In this form, the upper and lower grooves are made unnecessary by providing a full dome 30 and extending this to one side as at 31, where one side 32 of the clamp member is formed and coöperates with an 100 insulating clamping member 33, formed in lines of continuation of the extended portion 31 of the insulator body. To prevent lateral and other movements of the two clamping parts, an angularly-shaped 105 rib 34 and an angularly shaped groove 35 formed below the upper surface of the clamp member 33 register with similarly formed grooves and ribs 36, 37 also formed below the upper surface of the insulator 30. 110 Thus, there is a clean water-shed and highly resistant surface of maximum area interposed between the conductor and the pin or ground and the same advantageous clamping features are maintained.

In Figs. 14 and 15, the same idea of utilizing a clamp form such as shown in Figs. 10 and 11 with the ordinary type of petticoat insulator is illustrated. In these figures, the base-part 38 of the clamp conforms to the surface of the petticoat insulator 39 and the coöperating clamp member 40 is bound thereto by the usual clamping rod and nuts. This latter form, as in the case of Figs. 8 and 9, has certain advantages where 125 the invention is to be applied to petticoat insulators already in use and gives the additional insulation required and the additional advantageous features of providing an insulating clamp for the line wires. 130

It will be observed that in any of the forms the clamping members having their respective parts formed of insulating material increase the insulation between the 5 conductor and the ground and that in any of the various arrangements, the clamping parts will prevent drop of the wire in the event of the insulating parts being broken. Of course, it will be understood that the 10 form of the clamp opening may be of any desired style or type to meet the exigencies of any particular case, although the form illustrated will be effective for holding either twin wires or round wires.

15 Obviously, the exact form and detail of the respective parts is quite immaterial so long as the features of providing insulating clamping devices and the broken metallic holding devices are made features of the construction.

20 What I claim as my invention and desire to secure by Letters Patent is:

1. A line wire insulator consisting of a "petticoat" insulating body having a series 25 of grooves, an insulating boss forming a clamp member extending from one side thereof, a cooperating insulating clamp member, a line wire groove, and clamping devices encircling the groove of the insulating body-part and extending through the 30 clamp member on opposite sides of the wire groove for binding said insulating clamp members to a wire.

2. A line wire insulator having a body- 35 part of the "petticoat" insulator type, a boss extending from one side thereof, an insulating clamp member fitting said boss and adjustable for receiving a vertically or horizontally disposed wire, a cooperating clamp 40 member for clamping a wire against the adjustable clamp in either of its positions of adjustment on the petticoat insulator, and clamp devices for binding the insulating clamp members to the boss.

45 3. A line wire insulator consisting of an insulating body-part of "petticoat" type, a boss extending from one side thereof, an insulating clamp piece, said boss and clamp- 50 ing piece having interengaging recesses and projections for adjustably arranging said clamp piece upon the boss of the "petticoat"

insulator, an insulating clamping member for clamping a wire to the adjustable clamp member and clamping means for holding the parts clamped against a wire. 55

4. A line wire insulator consisting of an insulating body of "petticoat" type, a sectional insulating clamp having clamping members for a wire and having between them a wire opening at one side of said 60 "petticoat" insulator, and a metallic clamping device encircling the "petticoat" insulator and extending through the clamping members on opposite sides of the wire opening. 65

5. A line wire insulator consisting of an insulating body of "petticoat" type, a sectional insulating clamp having clamping members for a wire and having a wire opening at one side of said "petticoat" insulator, 70 a metallic clamping device encircling the "petticoat" insulator and extending through the clamping members on opposite sides of the wire opening and non-rotatable washer plates for the clamp device. 75

6. In a line wire insulator, an insulating body-part of "petticoat" type, a separable adjustable insulating clamp at one side thereof, a clamping device encircling the "petticoat" body-part and consisting of 80 two clamping members projecting through the separable clamp, washer plates engaging each of the clamping members and means for preventing relative rotation of the clamping members and washer plates, and 85 an insulating boss extending between the adjacent ends of the washer plates.

7. A line wire insulator, consisting of an insulating body-part of "petticoat" type, a boss projecting from one side thereof and 90 forming one section of a clamp, a cooperating insulating clamp member, interengaging ribs and grooves formed in the body of the clamp parts below the upper surface thereof and a clamp device engaging the "petticoat" 95 insulator and clamp parts for clamping a wire to the "petticoat" insulator.
